UNITED STATES PATENT OFFICE.

ELOF R. LEONARD, OF WOODCLIFF, NEW JERSEY.

SELF-CLOSING WINDOW.

1,256,335.

Specification of Letters Patent. Patented Feb. 12, 1918.

Application filed June 5, 1917. Serial No. 172,858.

To all whom it may concern:

Be it known that I, ELOF R. LEONARD, a citizen of the United States, residing at No. 209 Thirty-fourth street, Woodcliff, Bergen county, New Jersey, have invented certain new and useful Improvements in Self-Closing Windows, of which the following is a specification.

My invention relates to that class of windows wherein thermally actuated elements are used to control the action of weights adapted when released to automatically close the sashes. And my improvements are directed particularly to the arrangement of the weights and to the means for automatically transferring the influence of a weight or weights from the lower sash to the upper one, all of which I will proceed to describe, referring in so doing to the drawings in all of which similar parts are designated by corresponding reference numerals, Figure 1 being an inside elevation partly broken away, of a window frame and sashes embodying my invention; Fig. 2 being a side view of the casing, partly broken away, and looking to the left on Fig. 1; Fig. 3 being a vertical sectional view taken on the line 3—3 of Fig. 1, looking to the right; Fig. 4 being a detail on an enlarged scale of the upper portion of Fig. 3, the figure being shortened vertically by the omission of a medial portion; and Fig. 5 being a horizontal sectional view of the same taken on the line 5—5 looking down.

The casing 1 may preferably be made of sheet metal, in a conventional form, being provided with suitable flanges to form grooves between them for the upper and lower sashes, 2 and 4 to slide in in the usual manner.

The upper sash is balanced by weights 6, 6 connected to it by chains 7, 7, traveling over pulleys 8, 8, in the usual manner. The lower sash 4 is balanced by a chain 9, which is preferably carried around it, as shown by broken lines in Fig. 1, and is provided with fusible links as 10, 11 at different points in its course. The link 10, is attached to the chain above it by an enlarged member, as the S hook 12, the purpose of which will be later explained.

The chain 9 is carried up on each side over a pulley 13 in the top of the frame, then down around a pulley 14 to which is attached a weight 15 then up over a pulley 16 and down through the top of the casing, as shown in Fig. 4, and, a short distance below the top, the end of the chain is again preferably passed into the casing through a hole, as 17, which allows the slack of the chain to be disposed within the casing.

At the top of the casing, below the pulleys 13, 16 and intersecting the paths of the chain 9, is placed a key element 18, which is provided at one end with a finger 19 adapted to enter a link in the chain 9, and at the other end with a loop 22, through which the chain 9 may travel freely. A flange 20 engages in a slot or recess in the top of the casing to hold the key in position, with its shoulder 21 bearing against the top of the casing, while its end is some distance below the casing. The result of this arrangement is that if the looped end of the key is pushed up against the casing, the key will rock on the flange 20 as a pivot so as to withdraw its finger out of the link in the chain 9.

When the key is in the position shown in Fig. 4, its finger 19 locks the end of the chain with which it engages, and the lower sash is balanced by the weights 15, 15 hanging through their pulleys 14, 14 in the loops of the chain 9 between the pulleys 13, 16 on each side of the casing.

At the side of the casing a looped arm 23 is clamped, as by a bolt 24, or other suitable means, to that part of the chain 9 which normally is just below the pulley 16 in the interior of the casing when the chain 9 is held in position by the finger 19 of the key 18 as shown in Fig. 4. The loop of the arm 23, extends over and freely surrounds the chain 7 of the upper sash, with the normal movements of which it does not interfere inasmuch as the looped arm is well above the path of travel of the weights 6, 6. This arrangement may be duplicated on each side of the casing.

With the various parts in their normal positions the sashes can be freely raised and lowered and caused to pass each other without any interference of their weights, the

lower sash weights acting only on that sash and the upper sash weights only on that sash.

If, however, the chain 9 is severed by the melting of a fusible link, the lower sash, if raised, will fall of its own weight, and the chain will be immediately drawn down, by the weight 15, over the pulley 13, into the casing until the S hook strikes the looped end of the key 18, through which its size prevents it from passing. This will trip the key 18 up and draw its finger 19 out of the link in the chain 9 freeing that end of the chain. The weight 15 will then drag that end of the chain down within the casing carrying with it the looped arm 23 until it encounters the weight 6 of the upper sash, when, if that sash is lowered the additional drag of the weight 15 will immediately overbalance it and raise the sash.

It should be understood that preferably the arrangement of S hook, key 18, and looped arm 23, which I have described in detail for one side of the casing, is duplicated on the other side, although it is practicable, in narrow and smoothly running windows, to use the S hook on one side only and to connect it directly to the top of the lower sash by a fusible link.

To readjust the balancing mechanism it is only necessary to reconnect the released portions of the chain by a new fusible link, and to draw back the free ends of the chain over the pulleys 16, put the key 18 in proper position, and tuck the free ends of the chain into the casing through the openings 17.

By this means I secure an efficiently operating automatically closing window, positive in action, simple in readjustment, avoiding the necessity of opening the casing to recover or rearrange released parts, and in which there is no interference, under normal conditions, between the balancing mechanisms of the different sashes.

Having thus described my invention, what I claim and desire to secure by Letters Patent of the United States, is:—

1. The combination, in an automatically closing window, of a casing, an upper sash provided with counterbalancing means, a lower sash, counterbalancing means carrying the lower sash and embodying a flexible element having a fusible link, a carrying pulley over which the flexible element travels, a releasable detent attaching said flexible element toward one end to the casing, a pulley traveling upon a loop of said flexible element between said carrying pulley and said releasable detent, normally stationary connecting means between said flexible element and the upper sash counterbalancing means, said flexible element being also provided with means adapted to free the releasable detent from the flexible element upon the parting of said fusible link.

2. The combination, in an automatically closing window, of upper and lower sashes, normally independent counterbalancing means therefor, thermally governed means connecting the lower sash to an enlarged element in one portion of its counterbalancing means, a key element normally holding another portion of such counterbalancing means in fixed position, and means brought into action by the operation of said thermally actuated means for releasing said key element through the engagement of said enlarged element therewith to cause the lower sash counterbalancing means to operate upon the upper sash.

3. The combination, in an automatically closing window, of upper and lower sashes, normally independent counterbalancing means therefor, thermally governed means connecting the lower sash to one portion of its counterbalancing means, a key element normally holding another portion of such counterbalancing means in fixed position, connectible means between the counterbalancing means, and means brought into action by the operation of said thermally actuated means for releasing said key element from the counterbalancing means to cause the lower sash counterbalancing means to operate upon the upper sash through said connectible means.

4. The combination, in an automatically closing window, of an upper sash provided with counterbalancing weights and chains, a lower sash, a counterbalancing chain supporting the lower sash and embodying a tripping element and a fusible link, carrying pulleys over which said chain is carried to form a loop between them, a detent detachably attaching said chain to the casing beyond the carrying pulleys, a traveling pulley carried by said loop, a weight carried by the traveling pulley, a normally stationary connecting element attached to the lower sash chain and adapted to connect with an upper sash weight, said tripping element being adapted to cause said detent to release said lower sash chain upon the parting of the fusible link, and thereby to cause the connecting element to add the drag of the lower sash weight to the upper sash weight.

5. The combination, in an automatically closing window, of an upper sash provided with counterbalancing weights and chains, a lower sash, a counterbalancing chain supporting the lower sash and embodying on each side a tripping element and a fusible link, carrying pulleys on each side of the casing over which said chain is carried to form a loop between them, a detent detachably attaching said chain to each side of the casing beyond the carrying pulleys, a traveling pulley carried by each of said loops, a weight carried by each of the traveling pulleys, a normally stationary connecting ele-

ment attached to the lower sash chain at each side and adapted to connect with an upper sash weight, said tripping elements being adapted to cause said detents to release said lower sash chain upon the parting of a fusible link, and thereby to cause the connecting elements to add the drag of the lower sash weights to the upper sash weights.

ELOF R. LEONARD.
